(57) **CLAIM**

The ornamental design for a combined squeegee and sprayer, substantially as shown and described.

DESCRIPTION

FIG. 1 is a front, top, right perspective view of my design for a combined squeegee and sprayer in a closed configuration with the cap secured to cover the sprayer;

FIG. 2 is a rear, top, left perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a front, top, right perspective view for a combined squeegee and sprayer in an open configuration with the cap removed to show the sprayer;

FIG. 10 is a rear, top, left perspective view thereof;

FIG. 11 is a left side elevation view thereof;

FIG. 12 is a right side elevation view thereof;

FIG. 13 is a front elevation view thereof;

FIG. 14 is a rear elevation view thereof;

FIG. 15 is a top plan view thereof; and,

FIG. 16 is a bottom plan view thereof.
